UNITED STATES PATENT OFFICE.

EDWIN WELTE, OF FREIBURG, GERMANY, ASSIGNOR, BY MESNE ASSIGNMENTS, TO WELTE-MIGNON CORPORATION, OF NEW YORK, N. Y., A CORPORATION OF NEW YORK.

PNEUMATICALLY-CONTROLLED REGULATOR FOR MUSICAL INSTRUMENTS.

Application filed May 25, 1914. Serial No. 840,912.

To all whom it may concern:

Be it known that I, EDWIN WELTE, a subject of the Grand Duke of Baden, and a resident of Freiburg, in the Grand Duchy of Baden, German Empire, have invented certain new and useful Improvements in Pneumatically-Controlled Regulators for Musical Instruments, of which the following is a full, clear, and exact description, whereby anyone skilled in the art may make and use the same.

The invention relates to record controlled musical instruments, and particularly to certain improvements in the mechanisms employed to regulate and control the wind pressure or suction which is utilized to actuate the striker pneumatics, primary pneumatics or similar sounding devices and contemplates a control of a regulator which will give any and every modulation of action of the primary or striker pneumatics to so perfect a degree as to simulate and reproduce the actual playing of an operator.

These results can only be attained by modifying the wind pressures or suction and controlling the main source of power with reference to the striker pneumatics. Obviously, the whole control is dependent upon a variable attenuation of the pressure or suction acting upon the primary pneumatics and the present invention has to do with an automatic regulation of the main source of power with reference to the striker pneumatics, said regulation being variable and under automatic control so that there is practically no limit to the number of pressures and gradations of pressure or suction which it is possible to impress upon the striker pneumatics.

The object of the invention is to provide a controller intermediate the main source of power and primary or striker pneumatics which may be so modified in its action as to provide any attenuation of air pressure upon the striker pneumatics having given a maximum initial pressure in the main source of power.

The purposes of the invention are effected by arranging a regulator connected with the main source of power and the striker pneumatics and having connected with said regulator an automatically actuated mechanism which will intensify or diminish the normal effect of the main source of power upon the

regulator and consequently, upon the striker pneumatics.

The device, as illustrated in the drawings, is shown somewhat in diagram, it being considered unnecessary to illustrate all of the duplicate parts of the mechanism of an automatic instrument.

For convenience, the mechanism is illustrated in conjunction with an automatically and pneumatically operated player piano or piano player. The full details of the mechanism of the instrument are not illustrated, the art being so well understood as to make diagrams such as shown ample for the purposes of understanding the particular mechanism hereinafter described.

Referring to the drawings:

Fig. 1 is a diagrammatic view illustrating the relative arrangement of striker pneumatics, main source of power, controller and pneumatic valve actions for effecting manipulation of the controller.

Fig. 2 is a diagrammatic view on somewhat enlarged scale, illustrating particularly the controller and its connections to the automatic actuating devices and the primary pneumatics.

It is of course understood that the drawings herein do not attempt to illustrate all of the details of a musical instrument and it is believed the general class of such device is so well known that the diagrammatic representation of the main source of power, controlling devices, automatically actuated mechanism for modifying the action of the controlling devices and the connections to the primary or striker pneumatics are sufficient for a thorough understanding of the invention.

In Fig. 1, the various elemental parts are illustrated in duplicate as they would be applied to a musical instrument of the piano player or player piano type, wherein there is ordinarily employed a divided wind-chest to give independent action to the treble and bass or to sectional parts of the instrument and in the description of the device, a single set of elements is hereinafter referred to and it is to be understood that the mechanism particularly refers to the type of instrument in which a tracker-board is used and is controlled by a perforated music sheet. In a prior Patent, No. 1,008,291, issued Nov. 7th, 1911, there is illustrated a

system by which a valve controlling communication between a main source of power and a regulating bellows is controlled by the action of said regulating bellows and is modified in its control by an automatically actuated expression bellows. Obviously, in this prior patent there is disclosed in the regulating bellows, a means for maintaining a definite pressure of the main source of power 10 with reference to the striker pneumatics and there is also illustrated a regulating or expression bellows which will automatically vary the control of the main regulating bellows with reference to the main source of power and its action upon the striker pneumatics.

The invention hereinafter described, while analogous to that of my prior patent, shows a mechanism in which the regulator which 20 is connected with the main source of power and with the striker pneumatics is primarily a controlling element, in as much as, it is always in definite communication with a valve which controls communication between the main source of power and the regulator. To modify the action of this controller, a system of pneumatic devices having interconnected mechanical elements, retards or advances the action of the regulator 25 in such manner that said regulator, while always controlling its valve for maintaining any given pressure, will be varied in its control so that a multitude of pressures of different characters and degrees may be maintained by the regulator with reference to the striker pneumatics. This effect in the main, is produced by increasing or decreasing the resistance of the regulator and its connected controlling valve by a pneumatic 30 system which operates independently of, though primarily in conjunction with the induced pressures of the main source of power.

In the accompanying drawings there are 45 the usual feeders or exhaust bellows A which are in communication with a sustaining bellows or chamber B, this chamber representing the highest pressure of the system. The sustaining chamber B, through a duct b 50 communicates with a regulator D, which, as illustrated, is of the pneumatic bellows type and has a movable board d which, through a connection f, controls a valve F that governs the connecting duct b from the 55 main bellows.

The regulator D is in direct communication through a pipe g with the wind-passage G which is common to the several striker pneumatics H. It is understood, of course, 60 that there is a striker pneumatic for each note or tone producing device of the musical instrument and as illustrated herein, the striker pneumatic H is of the ordinary bellows type subject to inflation and deflation. 65 Each of the striker pneumatics H are,

through suitable tracker-ducks h connected with a tracker-board T. Upon venting of a tracker-opening which communicates with the tracker-ducks N, the primary or striker pneumatics are subjected to the then prevailing tension which is induced in the regulator D dependent upon the pressure in the regulator D and wind-passage G. The striker pneumatics act with greater or less force to produce corresponding effects upon the keys or notes of the instrument. The movable member d of the regulator D is normally distended by a spring K which is one element of a mechanical pneumatic system for producing variable resistant tension 70 upon the regulator D with a consequent variable regulation of the air through corresponding movements of the valve F.

As illustrated herein, the spring K is a cantilever spring, i. e., it has a substantially 85 flat longitudinally bendable portion having one end connected with the regulator board d, while the other end is connected to the movable member i of a pneumatic I, whereby it will be bent or flexed longitudinally in 90 accordance with the tensions of the air in the pneumatics I and D. Obviously, the condition of the pneumatic I will determine the resistant pressures of the spring K with reference to the regulator D.

The pneumatic I is pneumatically connected either to the main source of power or to natural atmospheric condition by a valve mechanism hereinafter described and the movable member i of the pneumatic I 100 is mechanically connected to this valve mechanism and is also connected to a pneumatically actuated mechanism controlled automatically from the tracker-board.

As illustrated in the drawings, the pneumatic I, through a duct 1 communicates with a valve chamber 2 which has a valve 3 controlling communication through a duct 4 with the main bellows or sustaining bellows B. The valve chamber 2 also has a valve 5 controlling communication to atmospheric air. Both the valve 3 and 5 are mounted upon a spindle 6 which has fixed abutments 7 and 8 which, upon a movement of the spindle 6 will move either of the valves 3 or 5. Said valves 3 and 5 are normally held to their seats by springs 8^a and 9 and upon an opening movement of the valve 3, the pneumatic I is subjected to the pressure or suction of the main bellows or sustaining bellows B and the spring K has its tension increased with reference to the regulator D.

Upon an opening of the valve 5, the pneumatic I is open to atmospheric pressure and distends, reducing the pressure of the spring K with reference to the regulator D.

The valve stem or spindle 6 is connected with what might be termed a hunting lever 10 which, through a rod 11, is connected 130

- with the movable member *i* of the pneumatic I. The lever 10 is pivoted to a movable bar 12, the position of which is controlled by a pneumatic 13 so that the fulcrum or pivot point of the lever 10, which is at 14 is variable in position. The lever 10 may turn about the point 14 as a fulcrum for controlling the valves 3 and 5, or, through the bar 12, it may be turned about 10 a point or fulcrum 15, where it joins the rod 11. From the above construction, it is apparent that if the point 14 is depressed by a movement of the bar 12, the valve 3 will be opened, subjecting the pneumatic I 15 to the suction of the main source of power B. This will immediately cause a partial collapse of the pneumatic I and an increase of tension of the spring K with reference to the regulator D. The movement of the 20 member *i* will be transmitted through the bar 11 to the hunting lever 10, which will shift upon its fulcrum 14 and immediately close the valve 3. In like manner, if the regulator D moves beyond a 25 normal fixed position requisite to pull upon the movable member *i* of the pneumatic I, the bar 11 will move the hunting lever 10 and open the valve 5 to atmosphere, whereupon the pneumatic I will expand.
- 30 From the above, it is apparent that there is always a definite balance which will maintain the regulator D in a definite fixed position unless the fulcrum 14 is varied in position by the pneumatic 13.
- 35 The pneumatic 13 is controlled in its movements and consequently controls the position of the bar 12 and fulcrum 14 of the hunting lever 10 through a system of valve actions controlled by the tracker-board of the instrument. The pneumatic 13 is controlled in its position and its operation upon the bar 12 and hunting lever 10 by ducts 17, 18 and 19. The duct 17 is larger in diameter and gives a more rapid 40 control to the pneumatic 13 than the duct 18, while the duct 19 actuates a pneumatic valve 20, subjecting the pneumatic 13 to atmospheric pressure and giving it an immediate opportunity to expand under the influence of its spring 21. Each of the ducts 45 17, 18 and 19 communicate with valve chambers which are respectively controlled by valves 22, 23, 24. Said valves control ports which communicate with a wind-chest 50 25, that is connected through a suitable duct 26 with the main source of power B. Each of the valves 22, 23, 24 are controlled by tracker-ducks which communicate with chambers located below diaphragms 27, 28, 55 29, so that as either of the corresponding ducts 30, 31, 32 of the tracker-board are vented, the valves controlled by the diaphragms will rise and place the ducts 17, 18, 19 in communication with the main suction. This in effect, will collapse the pneu-
- matic 13 to a greater or less extent and with greater or less speed, owing to the difference in the diameter of the ducts 17 and 18 or will permit immediate expansion or distension of the pneumatic 13 when the duct 19 70 opens the valve 20.
- The valve chambers in which the valves 22 and 23 are located communicate through ducts 33, 34 with the upper side of diaphragms 35, 36, so that either of said valves are held in unseated position with reference to the ports connecting with the wind-chest 25 until pressure is equalized upon the diaphragms by subjecting the under side thereof to the suction of the wind-chest 75 25 through ducts 37, 38. The duct 38 is controlled and admits atmospheric air or suction to the under side of the diaphragm 36 dependent upon the position of a valve 39 which is controlled by a tracker duct 40. 80
- To limit the movement of the pneumatic 13 or to hold it within definite limits of movement, a latch 41 is provided and this is pneumatically operated by a bellows or pneumatic 42 which communicates through a duct 43 with a valve chamber 44. This valve chamber 44 has a duplex valve 45 which controls a port 46, opening into the wind-chest 25 and a port 47 opening to the atmospheric channel 48 which channel is 90 common to the various valves of the system. The duplex valve 45 is controlled as to its position by a diaphragm 49, the chamber of which is vented through a tracker duct 50. The spindle of the valve 45 has, at its upper 100 end, a diaphragm 51, the upper side of which communicates with the valve chamber 44, while the lower side communicates with the valve chamber 52.
- The valve chamber 52 has a duplex valve 53 controlled as are the other valves of the system by a diaphragm 54, the chamber of which, through a duct 55 is vented through the tracker-board. 105
- The valves 45 and 53 control the inflation and deflation of the pneumatic 42.
- From the above, it is apparent that the pneumatic 13 may be moved to any desired degree, either rapidly or slowly, through the action of the main source of power and the ducts 17, 18, 19, which are under control from the tracker-board. It may also be confined in its movements by the pneumatic 42 which is also controlled automatically from the tracker-board. 115
- From this automatic control of the pneumatic 13, it is apparent that the hunting lever 10 may be moved to unseat the valve 3 in a great variety of positions and under an unlimited number of pressure conditions. The valve will be almost instantly re-seated by the re-action of the pneumatic I and therefore, there is an existing balanced condition always modifying the tension upon the movable member *d* of the 125 130

regulator D, which will, in effect, vary the position of the valve F and give an unlimited variation of pressures of the main source of power with reference to the regulator D and the striker pneumatics connected therewith.

It will be observed that the valve F which is the primary means of controlling the connection between the source of power and the regulator D is immediately under control of the regulator and that the effective regulation for varying the intensity of pressure upon the primary pneumatics is effected by modifying the resistance opposed to the natural action and tendency of the regulator D. This resistance is secured by a pneumatic system interposed between the regulator and the automatically controlling tracker-board. Through the pneumatic devices and their connection with the regulator D, an unlimited number of variations of pressure may be automatically secured upon the striker pneumatics through the control of the regulator. It is, of course, to be understood that the exact form of lever connection and arrangement of pneumatic devices is not absolutely essential, the purposes and intention of the invention being to give a variable resilient control upon the regulator which will cause said regulator to re-act and produce pressures of any possible intensity upon the striker pneumatics.

What I claim as my invention and desire to secure by Letters Patent is:

1. In a record controlled musical instrument, a main source of power, striker pneumatics, means providing a wind passage for the striker pneumatics and means to control communication of the striker pneumatics with the wind passage, in combination with means between the main source of power and wind passage to regulate the tension of the air in the wind passage, including a regulator operable to vary the said tension and to maintain uniformity of the tension to which it has been set regardless of the number of striker pneumatics operated simultaneously, an expression mechanism comprising two pneumatic means and a tension controlling means and mechanism between said pneumatic means and the tension controlling means whereby the movement of one of said means of the expression mechanism will affect the operation of another.

2. In a record controlled musical instrument, a main source of power, striker pneumatics, means providing a wind passage for the striker pneumatics and means to control communication of the striker pneumatics with the wind passage, in combination with means between the main source of power and wind passage to regulate the tension of the air in the wind passage, including a regulator operable to vary said

tension and to maintain uniformity of the tension to which it has been set regardless of the number of striker pneumatics operated simultaneously, and an expression mechanism comprising a plurality of interdependently-connected means connected to the regulator to vary the tension therein and record-controlled means acting with relation to the interdependently-connected means to effect the variable operation of said regulator.

3. In a record controlled musical instrument, a main source of power, striker pneumatics, means providing a wind passage for the striker pneumatics and means to control communication of the striker pneumatics with the wind passage, in combination with means between the main source of power and wind passage to regulate the tension of the air in the wind passage, including a regulator operable to vary said tension and to maintain uniformity of the tension to which it has been set regardless of the number of striker pneumatics operated simultaneously, and a record-controlled expression mechanism having connection with the regulator to control the operation thereof, the connection including a lever having a shiftable fulcrum.

4. In a record controlled musical instrument, a main source of power, striker pneumatics, means providing a wind passage for the striker pneumatics and means to control communication of the striker pneumatics with the wind passage, in combination with means between the main source of power and wind passage to regulate the tension of the air in the wind passage, including a regulator operable to vary said tension and to maintain uniformity of the tension to which it has been set regardless of the number of striker pneumatics operated simultaneously, a tensioning device connected with the regulator, a lever having a shiftable fulcrum, connections between said lever and tensioning device, and record controlled means connected to said lever to operate the same.

5. In a record controlled musical instrument, a main source of power, striker pneumatics, means providing a wind passage for the striker pneumatics and means to control communication of the striker pneumatics with the wind passage, in combination with means between the main source of power and wind passage to regulate the tension of the air in the wind passage, including a regulator operable to vary said tension and to maintain uniformity of the tension to which it has been set regardless of the number of striker pneumatics operated simultaneously, a variable resistant tensioning device connected to the regulator, interdependently-connected means to operate said device to vary the resistance im-

- posed by it upon the regulator, said means including a controlling lever having a shiftable fulcrum, and record-controlled means to actuate said lever.
6. In a record controlled musical instrument, a main source of power, striker pneumatics, means providing a wind passage for the striker pneumatics and means to control communication of the striker pneumatics with the wind passage, in combination with means between the main source of power and wind passage to regulate the tension of the air in the wind passage, including a regulator operable to vary said tension and to maintain uniformity of the tension to which it has been set regardless of the number of striker pneumatics operated simultaneously, a variable resistant tensioning device connected to the regulator, including a pneumatic having a movable member and a resilient connection between said member and the regulator, a lever having a shiftable fulcrum, means controlled by said lever to vary the tension of the air in the pneumatic, a connection between said lever and the movable member of the pneumatic, and record-controlled means to actuate said lever.
7. In a record controlled musical instrument, a main source of power, striker pneumatics, a regulator between the main source of power and the striker pneumatics, a variable tension device acting upon said regulator, pneumatic connections between the main source of power and the tension device and means to control said connections, said means having a separate connection to the tension device.
8. In a record controlled musical instrument, a main source of power, striker pneumatics, a regulator between the main source of power and the striker pneumatics, a variable tension device acting upon said regulator, valved pneumatic means through which the main source of power is connected to the tension device, and record-controlled means having one connection to the tension device and another connection to the valved pneumatic means for the purpose set forth.
9. A regulating device for musical instruments comprising a regulating pneumatic communicating with the main source of power and with the striker pneumatics, a valve controlled by said regulator, a tension device connected with the regulator and comprising a spring and a pneumatic controlling the position thereof to thereby vary its tension, connections intermediate said pneumatic and the main source of power, valves controlling said connections to the main source of power and to the atmosphere, a lever connecting said valves and the pneumatic of the spring tension device and record controlled acuated devices for shifting the fulcrum point of said lever whereby the controlling valves may be effected by the pneumatic or by the automatic devices.
10. A regulator for musical instruments comprising a regulating pneumatic and its valve, said pneumatic communicating with a main source of power and with the striker pneumatics, a tensioning pneumatic having a resilient connection with the regulating pneumatic, valves for connecting said tensioning pneumatic with the atmosphere or with the main source of power for varying the tension of the resilient connection, a lever connecting said tensioning pneumatic and valves and an automatic device for operating said valves independently of the action of the pneumatic.
11. A regulator for musical instruments comprising a regulating pneumatic and its valve, said pneumatic communicating with a main source of power and with the striker pneumatics, a controlling pneumatic having a resilient connection with the regulating pneumatic, valves for connecting said controlling pneumatic with the atmosphere or with the main source of power for varying the tension of the resilient connection, a lever connecting said controlling pneumatic and valves and an automatic device for operating said valves independently of the action of the controlling pneumatic, said automatic device having a variable speed of movement with reference to the lever.
12. A regulator for musical instruments comprising a regulating pneumatic and its valve, said pneumatic communicating with a main source of power and with the striker pneumatics, a controlling bellows having a resilient connection with the regulating pneumatic, valves for connecting said controlling pneumatic with the atmosphere or with the main source of power for varying the tension of the resilient connection, a lever connecting said controlling pneumatic and valves and an automatic device for operating said valves independently of the action of the controlling pneumatic, said automatic device having automatically controlled pneumatic actions controlling the main source of power with reference to said automatic device and tracker connections for adjusting said actions.
13. In a record controlled musical instrument, a main source of power, striker pneumatics, a regulator between the main source of power and striker pneumatics, a variable resistant tensioning means acting upon the regulator, said tensioning means including a pneumatic, valvular means for controlling the air in the pneumatic, connecting means connected to the valvular means and to the pneumatic, and record-controlled controlling means connected to the connecting means.
14. In a record controlled musical instru-

ment, a main source of power, striker pneumatics, a regulator between the main source of power and striker pneumatics, a variable resistant tensioning means acting upon the 5 regulator, said tensioning means including a pneumatic, valvular means for controlling the air in the pneumatic, connecting means including a lever having a shiftable fulcrum connected to the valvular means and to the 10 pneumatic, and record-controlled controlling means connected to the connecting means.

15. In a record controlled musical instrument, a main source of power, striker pneumatics, a regulator between the main source 15 of power and striker pneumatics, a variable resistant tensioning means having a pneumatic connected to the regulator, a valvular mechanism for controlling the tension of the air in the pneumatic, including chambers for 20 airs of different tensions respectively, an additional chamber having communication with the pneumatic, ports through which the additional chamber may have communication with either of the other chambers, 25 valve members to control said communication, respectively, a spindle upon which the valve members are mounted, means to hold the valve members normally to their seats, means whereby the movement of the spindle 30 in one direction unseats one valve and its movement in the other direction unseats the other valve, and record-controlled means to move said spindle.

16. In a record controlled musical instrument, a main source of power, striker pneumatics, a regulator between the main source 35 of power and striker pneumatics, a variable resistant tensioning means having a pneumatic connected to the regulator, a valvular mechanism for controlling the tension of the air in the pneumatic, including chambers for 40 airs of different tensions respectively, an additional chamber having communication with the pneumatic, ports through which the additional chamber may have communication 45 with either of the other chambers, valve members to control said communication, respectively, a spindle upon which the valve members are mounted, means to hold the 50 valve members normally to their seats means whereby the movement of the spindle in one direction unseats one valve and its movement in the other direction unseats the other valve, and record-controlled means including a lever having connection 55 with the spindle and with the pneumatic for the purposes set forth.

17. In a record-controlled musical instrument, a main source of power, striker pneumatics, a regulator in the connection between the main source of power and striker pneumatics, a tensioning member acting upon the regulator, pneumatic connections including valve members between the tensioning member and the main source of power

and atmosphere, a spindle to open the valves severally, said members being movable relatively to the spindle and having means tending to close them, respectively, and record controlled operating means connected to the 70 spindle.

18. In a record-controlled musical instrument, a main source of power, striker pneumatics, a regulator in the connection between the main source of power and striker pneumatics, a tensioning member acting upon the regulator, pneumatic connections including valve members between the tensioning member and the main source of power and atmosphere, a spindle to open the valves severally, said members being movable relatively to the spindle and having means tending to close them, respectively, a mechanical connection between the tensioning member and valve spindle, and record controlled 80 means connected to said connection to move the same.

19. In a record controlled musical instrument, a main source of power, striker pneumatics, means providing a wind passage for 90 the striker pneumatics, means to control communication of the striker pneumatics with the wind passage, a regulator comprising a member whose interior is in communication with the main source of power and with the wind passage and also comprising a pivotally mounted valve to control communication of the interior of said member with the source of power and wind passage 95 and means connecting the regulator member with the valve, a motor pneumatic, a spring connection controlled by the motor pneumatic and in turn controlling the regulator valve through the regulator member, the connections from the regulator to the motor 100 pneumatic and to the valve being out of alignment, and record-controlled means having connection with the main source of power and with the motor pneumatic to actuate the latter to vary the tension of the 105 spring connection.

20. In a record controlled musical instrument, a main source of power, striker pneumatics, means providing a wind passage for 110 the striker pneumatics, means to control communication of the striker pneumatics with the wind passage, a regulator comprising a member whose interior is in communication with the main source of power and with the wind passage and also comprising a valve to control communication of the interior of said member with the source of power and wind passage and means connecting the regulator member with the valve, a motor pneumatic, a spring having a 115 cantilever action interposed between the motor pneumatic and the regulator member to be controlled by the motor pneumatic and in turn to control the regulator valve through said member, said spring having one end 120

rigidly secured to the movable member of the motor pneumatic, and record controlled means having connection with the main source of power and with the motor pneumatic to actuate the latter to vary the tension of the spring.

21. In a record controlled musical instrument, a main source of power, striker pneumatics, means forming a wind passage for the striker pneumatics, means to control communication of the striker pneumatics with said wind passage, a regulator comprising a member whose interior is in communication with the main source of power and with the wind passage and also comprising a pivotally mounted valve to control communication of the interior of said member with the source of power and wind passage and a connection between said member and valve, a motor pneumatic, a spring having a cantilever action controlled by the motor pneumatic and in turn controlling the regulator valve through said member, said spring having one end rigidly secured to the movable member of the motor pneumatic, and record controlled means having connection with the main source of power and with the motor pneumatic to actuate the latter to vary the tension of the spring.
22. In a record controlled musical instrument, a main source of power, striker pneumatics, means forming a wind passage for the striker pneumatics, means to control communication of the striker pneumatics with said wind passage, a regulator having a duct through which it has communication with the source of power and a second duct through which it has communication with the wind passage, said regulator comprising a bellows and a pivotally-mounted valve, the valve operatively related to one of the ducts and operatively connected to the movable member of the bellows, a second bellows, a spring having a cantilever action secured at one end to the movable member of the second bellows, said spring having one end rigidly secured to the movable member of the second bellows, means connecting the other end of the spring to the movable member of the regulator bellows and record controlled means having connection with the main source of power and with the main second bellows to actuate the latter to vary the tension of the spring, for the purposes set forth.
23. In a record controlled musical instrument, a main source of power, striker pneumatics, means forming a wind passage for the striker pneumatics, means to control communication of the striker pneumatics with said wind passage, a regulator having a duct through which it has communication with the source of power and a second duct through which it has communication with the wind passage, said regulator comprising a bellows and a pivotally-mounted valve, the valve being operatively related to one of the ducts and operatively connected to the movable member of the bellows, a motor pneumatic, a spring connection between the motor pneumatic and movable member of the bellows, the connections from the regulator to the motor pneumatic and to the valve being out of alignment, and record controlled means having connection with the main source of power and with the motor pneumatic to actuate the latter to vary the tension of the spring, for the purposes set forth.
24. In a record controlled musical instrument, a main source of power, striker pneumatics, means forming a wind passage for the striker pneumatics, means to control communication of the striker pneumatics with said wind passage, a regulator having a duct through which it has communication with the source of power and a second duct through which it has communication with the wind passage, said regulator comprising a bellows and a pivotally-mounted valve, the valve operatively related to one of the ducts and operatively connected to the movable member of the bellows, a second bellows, a spring having a cantilever action secured at one end to the movable member of the second bellows, said spring having one end rigidly secured to the movable member of the second bellows, means connecting the other end of the spring to the movable member of the regulator bellows, and record controlled means having connection with the main source of power and with the main second bellows to actuate the latter to vary the tension of the spring, for the purposes set forth.

pneumatics, means forming a wind passage for the striker pneumatics, means to control communication of the striker pneumatics with said wind passage, a regulator having a duct through which it has communication with the source of power and a second duct through which it has communication with the wind passage, said regulator comprising a bellows and a valve, the valve operatively related to one of the ducts and operatively connected to the movable member of the bellows, a second bellows, a spring having a cantilever action secured at one end to the movable member of the second bellows, said spring having one end rigidly secured to the movable member of the second bellows, means connecting the other end of the spring to the movable member of the regulator bellows and record controlled means having connection with the main source of power and with the main second bellows to actuate the latter to vary the tension of the spring, for the purposes set forth.

25. In a record controlled musical instrument, a main source of power, striker pneumatics, means forming a wind passage for the striker pneumatics, means to control communication of the striker pneumatics with said wind passage, a regulator having a duct through which it has communication with the source of power and a second duct through which it has communication with the wind passage, said regulator comprising a bellows and a pivotally-mounted valve, the valve operatively related to one of the ducts and operatively connected to the movable member of the bellows, a second bellows, a spring having a cantilever action secured at one end to the movable member of the second bellows, said spring having one end rigidly secured to the movable member of the second bellows, means connecting the other end of the spring to the movable member of the regulator bellows, and record controlled means having connection with the main source of power and with the main second bellows to actuate the latter to vary the tension of the spring, for the purposes set forth.

EDWIN WELTE.
